UNITED STATES PATENT OFFICE.

JOHN H. VINTON, OF BOSTON, MASSACHUSETTS, ASSIGNOR TO THE PENINSULAR NOVELTY COMPANY, OF GRAND RAPIDS, MICHIGAN.

BUTTON-FASTENING MACHINE.

SPECIFICATION forming part of Letters Patent No. 368,631, dated August 23, 1887.

Application filed June 15, 1886. Serial No. 205,235. (No model.)

To all whom it may concern:

Be it known that I, JOHN H. VINTON, of Boston, county of Suffolk, and State of Massachusetts, have invented an Improvement in 5 Button-Fastening Machines, of which the following description, in connection with the accompanying drawing, is a specification, like letters on the drawing representing like parts.

This invention has for its object to improve 10 button-setting machines of the class represented in United States Patent No. 312,987, whereby staples contained within a staple raceway or chute, and having buttons loosely connected therewith, are permitted to follow 15 down said chute and pass diagonally or laterally under, and so as to be struck by a descending driver.

In accordance with this invention the staple-carrier, its slide, and the driver are carried 20 by a movable head. The staple-chute employed is inclined or bent inwardly at its lower end, to thus permit the staples and attached buttons to enter the staple-carrier in position beneath the driver to be struck by the latter, 25 feeding-devices to govern the passage of the staples and buttons to the carrier being connected with the staple-chute and controlled automatically by the rising and falling head.

The drawing shows in side elevation a button-setting machine embodying this invention, 30 a portion thereof being broken away to more clearly show the operating parts.

The main frame-work consists of a post, *a*, an arm, *b*, supporting an anvil, *b'*, and an arm, 35 *b''*. A head, *c*, fixed to the top of a shank, *c'*, moving within the post *a*, and connected to any suitable treadle, (not shown,) carries a driver, *c''*, rigidly connected therewith, and a staple-carrier slide *c'''*.

The staple-carrier slide *c'''* is connected to a 40 rod, *c''*, moving within an overhanging arm, *c'*, and encircled by a spiral spring, *c'*, which normally tends to keep the staple-carrier slide in elevated position. The staple carrier or 45 block *e*, located at the lower end of the staple-carrier slide, is slotted and recessed to receive a staple having a button loosely connected therewith, substantially as in the patent referred to, the said staple-carrier being so located as to permit the driver to enter and force 50

therefrom a staple when the head *c* is depressed, the staple-carrier slide yielding against the spring *c'*.

The staple-chute *f* consists of a raceway substantially rectangular in cross-section, and slotted to receive a staple having a button loosely connected therewith, said staple-chute being bent inwardly, as at *f'*, at its lower end and terminating contiguous to the staple-carrier *e*, so that the endmost staple within the 55 staple-chute may drop directly into the staple-carrier. The staple-chute is secured to the front end of the arm *b''* by suitable screws, or otherwise, to thus remain stationary.

Suitable feed-dogs, *n* *n'*, pivoted to projections upon the rear side of the staple chute or guide and having their engaging ends turned toward each other, are provided to allow the staples within the staple-chute to pass out one at a time. The feed-dogs *n* *n'* are operated by 60 two pins, 2 3, attached to the moving head *c*, so that as the said head rises and falls first one and then the other feed-dog is operated to allow one staple to pass as the head rises and falls, the two pins striking the cam-shaped 70 surfaces of the feed-dogs and turning them on their pivots.

The staples having buttons loosely connected therewith are placed within the staple-chute, one being allowed to pass the feed-dogs and 80 enter the staple-carrier *e*. The treadle is then operated and the staple-carrier descends, bearing upon the material placed upon the anvil *b'*, it then yielding, permitting the driver to force the staple from the staple-carrier. During such operation the pin 2 turns the feed-dog *n* and allows the next staple to fall upon the feed-dog *n'*. As the head *c* rises, the dog *n* is released and the pin 3, striking the dog *n'*, allows that staple resting upon it to drop, following the inclined portion *f'* of the staple-chute and entering the staple-carrier *e*. Thus it will be seen that at each operation of the machine one staple is allowed to pass the feed-dogs and enter, by means of the inwardly-bent 95 staple chute, in suitable position to be struck by the descending driver.

It is obvious that the feed-dogs may be variously positioned and operated in different ways yet accomplishing the results herein 100

stated, so I do not desire to limit my invention to the specific construction and location shown.

It will be seen that the staple-carrier lying contiguous to the termination of the bent staple-chute forms, when taken collectively, a single staple guide or chute, so shaped as to convey the staples from the raceway to a position directly beneath and so as to be struck by the driver.

I do not herein broadly claim a button-setting machine containing a carrier or chute slotted to receive one or more staples having buttons attached thereto, and having an inward bend or offset at its lower end to receive the staple and attached button, combined with a driver to free the lowermost staple from said inward bend or offset, as the same is not of my invention.

20 I claim—

In a button-setting machine, a chute or guide slotted to receive staples and attached buttons, and bent inwardly at its lower end to convey the staples to a position directly beneath and so as to be struck by the driver to set the button, combined with feed-dogs, and means, substantially as described, to operate them to permit one staple and its attached button to pass and be conveyed by the bent chute or guide beneath the driver at each operation of the machine, substantially as set forth.

In testimony whereof I have signed my name to this specification in the presence of two subscribing witnesses.

JOHN H. VINTON.
